ATTORNEY

UNITED STATES PATENT OFFICE.

DAVID G. FUCHS, OF PITTSBURGH, PENNSYLVANIA.

SPARK PLUG.

Application filed October 16, 1923. Serial No. 668,925.

This invention relates to spark plugs for use in internal combustion engines, and more particularly to a spark plug having a visible spark gap for indicating whether the plug is sparking properly.

One of the main objects of the invention is to provide a spark plug of simple construction and operation having a visible indicating spark gap which is connected in series with the firing spark gap in such a manner that a spark cannot pass across the visible spark gap until after sparks have passed across the firing spark gaps at the inner end of the plug. A further object is to provide a spark plug by means of which a plurality of sparks may be caused within the cylinder for firing the explosive charge. Further objects will appear from the detail description.

20 In the drawings:—

Figure 1 is an elevation of the spark plug;

Figure 2 is a central vertical section through the spark plug taken substantially on line 2—2 of Fig. 3;

25 Figure 3 is an underneath end view of the spark plug.

The plug includes a body 1 of a known construction adapted to be threaded into the head of a cylinder of an internal combustion engine. This body receives a core 2 of porcelain or other suitable electrical insulating material, which core is provided, at its central portion, with an annular shoulder 3 which fits into body 1. A packing gland 4 is threaded into the upper portion of body 1 and bears against shoulder 3 for securing core 2 in position. A terminal pin 5 is secured in gland 4, the upper end of this pin being spaced away from the upper end of an electrical conductor 6 so as to form a visible spark gap 7. The conductor 6 is encased within core 2 and extends longitudinally thereof, this conductor extending beyond the lower end of the core and being bent substantially at right angles to form a terminal element or sparking point 8. A second conductor 9 similar to conductor 6 is encased within core 2, this second conductor being disposed diametrically opposite to conductor 6 and terminating, at its upper end, in a binding post 10 connected to conductor 9 by an inclined portion 9^a. At its lower end

conductor 9 is provided with a terminal element or sparking point 11 which is directed oppositely to terminal element 8. A 55 central pin or electrode 12 of electrical conducting material is secured within core 2 and projects below the same, this pin being positioned between and equidistant from spark points 8 and 11. This provides firing 60 spark gaps 13 and 14 between the central electrode or pin 12 and the spark points 8 and 11, respectively.

When the plug constructed in the manner illustrated and described is secured in the 65 head of the cylinder, the binding post 10 is connected to one side of a suitable source of electrical energy the other side of which is grounded to the engine, in a known manner. The current passes from binding post 70 10 through conductor 9 and jumps from spark point 11 across spark gap 14 to pin 12, the current then jumping from pin 12 across spark gap 13 to spark point 8 and flowing through conductor 6 to point 6^a 75 from which point the current jumps across visible spark gap 7 to pin 5 and thence to ground and back to the other side of the battery or other source of electrical energy. By constructing the plug in this manner 80 I obtain two sparks within the cylinder so as to insure proper firing of the explosive mixture and a third spark is created across the visible spark gap 7 so that the user can readily determine at a glance if the plug 85 is firing properly. It is to be noted that there will be no spark across gap 7 until after the current has jumped across the gaps 13 and 14 so as to produce the sparks within the cylinder. By this arrangement, if the 90 plug sparks across gap 7 this is a reliable indication that the plug is sparking properly within the cylinder.

What I claim is:—

In a spark plug, a body of electrical conducting material, a core of electrical insulating material mounted in the body, a packing member of electrical conducting material threaded into the body and cooperating therewith to secure the core, a pin of electrical conducting material secured in the core and projecting from the lower end thereof, two electrical conductors carried by the core and insulated thereby from each other and

from the pin as well as from the body and the packing member, said conductors being provided with terminal elements disposed adjacent and at opposite sides of the pin, means for connecting one of the conductors to one side of a source of supply of electrical energy, and a terminal pin of electrical con-

ducting material carried by the packing member, the upper end of the other conductor projecting beyond the core and being ¹⁰ spaced from said terminal pin to form therewith a visible spark gap.

In testimony whereof I affix my signature.

DAVID G. FUCHS.
